(57) **CLAIM**

The ornamental design for a two-piece toilet, as shown and described.

DESCRIPTION

FIG. 1 is a perspective view of a one-piece toilet;

FIG. 2 is a front elevation view of the one-piece toilet of FIG. 1;

FIG. 3 is a back elevation view of the one-piece toilet of FIG. 1;

FIG. 4 is a right side elevation view of the one-piece toilet of FIG. 1;

FIG. 5 is a left side elevation view of the one-piece toilet of FIG. 1;

FIG. 6 is a top plan view of the one-piece toilet of FIG. 1; and,

FIG. 7 is a bottom plan view of the one-piece toilet of FIG. 1.

The broken line shown in the drawings are for the purpose of illustrating a portion of the toilet that forms no part of the claimed design.
